UNITED STATES PATENT OFFICE.

ARTHUR WURDACK, OF NORMANDY, MISSOURI.

DESIGN FOR A ROCKER SWING.

Application filed October 13, 1923. Serial No. 7,491. Term of patent 14 years.

To all whom it may concern:

Be it known that I, ARTHUR WURDACK, a citizen of the United States of America, residing at Normandy, St. Louis County, in the State of Missouri, have invented a new, original, and ornamental Design for a Rocker Swing, of which the following is a specification, reference being had to the accompanying drawing, forming part thereof.

Figure 1 is a front elevational view of the article, and

Figure 2 is an end view of the same.

I claim:

The ornamental design for a rocker-swing, as shown.

ARTHUR WURDACK.
